Primary Examiner — Mary Ann Calabrese*Assistant Examiner* — Hillary Catherine Shepard(74) *Attorney, Agent, or Firm* — Jose Cherson Weissbrot(57) **CLAIM**

The ornamental design for a cabinet, as shown and described.

DESCRIPTION

FIG. 1 is a front, top, and right perspective view of a cabinet, showing my new design;

FIG. 2 is a rear, bottom, and left perspective view thereof; FIG. 3 is a front, bottom, and rear perspective view thereof;

FIG. 4 is a front elevational view thereof;

FIG. 5 is a rear elevational view thereof;

FIG. 6 is a left side view thereof, the right side view being a mirror image of FIG. 6; and,

FIG. 7 is a top plan view thereof.

The broken lines in the figures are for the purposes of illustrating portions of the cabinet, which form no part of the claimed design.
